UNITED STATES PATENT OFFICE.

GASTON AMEDEE MOURLAQUE, OF PARIS, FRANCE.

METHOD AND APPARATUS FOR MAKING PAPER.

Application filed October 4, 1927, Serial No. 223,972, and in France August 22, 1927.

My invention relates to an apparatus and a method utilized in the manufacture of paper dough.

Up to the present time vegetable matter 5 has generally been treated with a soda or bisulfite of soda wash in cylindrical or spherical boilers heated by the circulation of steam from a separate generator necessitating numerous expenses in both labor and material 10 and namely high expense in the purchasing of chemical products for the preparation of lixiviums.

A further expense is incurred in the necessary evaporating ovens for the recovery of 15 the residuary lixiviums as much as possible.

The present invention has for an object a boiler arrangement with an interior hearth for transforming vegetable matter into paper dough by oxidation with ozone and lixiviation 20 by means of the vegetable matter cinders. This arrangement has the advantage of eliminating the numerous pieces of apparatus heretofore mentioned as well as the manual labor connected therewith. Further 25 advantages of the arrangement are the recovery by evaporation and calcination in the said hearth of the residuary lixiviums, the recovery of the cinders of the vegetable matter which serves as a combustible for the 30 preparation of the lixiviums, the washing and bleaching of the paste once the heating process is terminated without dangerous manipulation as well as the dehydration in said hearth of the necessary limestone for 35 the caustification of the carbonate of potassium obtained from said cinders in order to liberate the alkali.

The accompanying drawing shows a perspective view of my apparatus with parts 40 broken away to show the interior.

My apparatus comprises a casing of sheet steel A. Said casing forms in effect a sort of boiler and is provided on the interior with a firebox C formed of a sheet metal member H₂ 45 and a header H₁. The remaining portion of the interior of said casing A provides a steam and water space B.

Firerubes H are connected to said header and communicate with a stack O provided 50 with a damper O' passing through the steam and water space B.

In the space B is adapted to slide a basket B' of open construction and mounted on rails I by means of rollers I' disposed on the top 55 of the firebox C.

Disposed within the firebox C is a grate

C' beneath which is placed a rotary shaker Q for causing the cinders therefrom to drop into a sifter E fixed beneath the apparatus.

At the bottom of the space B is provided an outlet D provided with a valve D' for allowing the residuary lixiviums given off by the heating process to be collected in suitable receptacles for the purpose of returning them to the firebox for recovering the potash and burning the decomposed organic materials of the vegetable material.

The space B is closed at the front with a door F provided with hermetically sealing pressure screws F' to permit the basket B' 70 to be introduced therein.

On the top of the space B is provided a steam dome L, provided with a steam outlet L' in which is disposed a valve L₂, a steam gauge M, a safety valve K and a water gauge 75 G only part of which is shown. Communicating with the space B is also a feed water pipe N provided with a valve N'.

The fire box is provided with a door R for obtaining access thereto and injectors P for 80 projecting the residuary water of the heating process by atomization. The water is transformed into steam and escapes by stack O thereby accelerating the draft therein. The solid material decomposed from the 85 vegetable matter such as vasculose, pectose and the like is calcinated and transformed into cinders and becomes added to those of the hearth. The potash is likewise recovered and is mixed with the cinders for the preparation of other lixiviums.

The manner of operating my apparatus and the chemical process performed thereby is as follows:

The basket B' is first filled with vegetable 95 matter previously cut into small pieces and then introduced into the space B of casing A.

Door F is then sealed hermetically by means of its pressure screws F' and water is introduced into the space B through the inlet pipe N until the vegetable matter to be treated in basket B' is covered. The vegetable matter is allowed to soak in the water for about an hour until well inbibed after which the water is withdrawn from the space B 105 by means of the outlet D.

Previously ozonized air of a suitable concentration is then introduced into the space B at a pressure of from 3 to 4 atmospheres for a period of about two hours according to 110 the character of the vegetable matter being treated and the degree of oxidization desired.

Since ozone has the property of oxidizing to a degree 40 times as great as that of chlorine and to resinify without attacking the so-called cellulose, it follows that the incrustations materials of the vegetable matter will be easily dissolved in the lixiviums of potassium under pressure.

The ozone is then evacuated from the space B after which it is filled with a lixivium of potassium previously prepared to the proper degrees Baumé according to the vegetable matter under treatment and the paste to be obtained by lixiviation of the cinders of the vegetable matter after having served as a combustible. The carbonate of potassium thus obtained will be subsequently caustified when quicklime is added in suitable proportions which is obtained as previously mentioned by dehydrating limestone in the firebox C during roasting of the vegetable matter.

The fire is then lighted in the firebox and the pressure in space B is then gradually brought up to from 3 to 8 kilograms which pressure is held during the time necessary to treat the vegetable matter and obtain the quality of paste desired.

After the roasting has terminated the pressure is reduced by opening the escape valve L₂ on the dome L.

After the steam has all escaped the space B is again filled with ordinary water for washing and cooling the paste obtained. If it is desired to bleach the paste before its removal, the space B is filled with a suitable bleaching agent under pressure, such as, chlorine, ozone, hypochlorite or the like, after which, if the agent used is of a gaseous nature it is allowed to escape through escape valve L₂ or by running water through the space B by means of inlet N and outlet D if the agent is of a liquid nature.

The operations above described produce a slightly dark paper paste but sufficiently bleached if the bleaching process above described has been carried out in the apparatus.

The paste thus obtained is suitable for the manufacture of wrapping paper, printing paper or even paper of the finer grades which is formed into sheets by any of the processes known in the art.

During the heating process above described the injector P may be operated for recovering the residuary lixiviums of the different operations described. Also during said heating operation limestone for dehydration is introduced into the firebox C by means of the door R, which lime is used for the purpose above mentioned.

Having thus described my invention what I claim as new and desire to secure by Letters Patent is—

1. The method of obtaining a paper paste from vegetable substances, which comprises, soaking a quantity of vegetable matter in

water, withdrawing said water, treating said vegetable matter with ozone, subsequently treating said vegetable matter with a lixivium of potassium, adding quicklime to the said vegetable matter, heating said vegetable matter and allowing it to be subjected to pressure and washing and bleaching the paste thus formed, said lixivium of potassium being prepared from the ashes of the combustible used in heating said vegetable matter. 70

2. The method of obtaining a paper paste from vegetable substances, which comprises, soaking a quantity of vegetable matter in water, withdrawing said water, treating said vegetable matter with ozone, subsequently 80 treating said vegetable matter with a lixivium of potassium, adding quicklime to the said vegetable matter, heating said vegetable matter and allowing it to be subjected to the pressure generated thereby and washing and bleaching the paste thus obtained, said lixivium of potassium being prepared from the ashes of the combustible used in heating said vegetable matter and said quicklime being obtained by dehydrating limestone by said 90 combustible.

3. A method according to claim 1 in which the said operations are all carried out within the limits of a single casing.

4. A method according to claim 2 in which the said operations are all carried out within the limits of a single casing. 95

5. The method of obtaining a paper paste from vegetable substances, which comprises, soaking a quantity of vegetable matter in 100 water, withdrawing said water, treating said vegetable matter with ozone, subsequently treating said vegetable matter with a lixivium of potassium, adding quicklime to the said vegetable matter, heating said vegetable matter and allowing it to be subjected to the pressure generated thereby, washing the 105 paste thus obtained, bleaching said paste, said lixivium of potassium being prepared from the ashes of the combustible used in heating said vegetable matter and recovering the residuary lixiviums of the combustible by evaporation and calcination.

6. The method of obtaining a paper paste from vegetable substances, which comprises, soaking a quantity of vegetable matter in water, withdrawing said water, treating said vegetable matter with ozone, subsequently treating said vegetable matter with a lixivium of potassium, adding quicklime to the said vegetable matter, heating said vegetable matter and allowing it to be subjected to the pressure generated thereby, washing the paste thus obtained, bleaching said paste, said lixivium of potassium being prepared from the ashes of the combustible used in heating said vegetable matter and recovering the residuary lixiviums of the combustible by evaporation and calcination, the said calcinating process furnishing the said quicklime. 130

7. An apparatus for obtaining paper paste comprising in combination, a casing, a firebox in said casing, firetubes associated with said firebox, a steam and water space surrounding said firebox and said firetubes, an inlet pipe for said steam and water space, an outlet pipe for said steam and water space, a steam dome associated with said steam and water space, a steam exhaust connected to said steam dome, 10 a hermetically sealed door for said steam and water space and means for introducing vegetable matter for treatment into said steam and water space for the purpose described.

8. An apparatus according to claim 7, in which said means comprises a wire basket

15 mounted on rollers sliding on rails provided in said steam and water space.

9. An apparatus according to claim 7, in which said firebox is provided with a grate, a shaker beneath said grate and a sieve beneath 20 said shaker for recovering the cinders of said firebox.

10. An apparatus according to claim 7, in which said firebox is provided with an injector for recovering the residuary lixiviums 25 of the combustible supplied to said firebox.

In testimony whereof, I have signed my name to this specification at Paris this 22nd day of September, 1927.

GASTON A. MOURLAQUE.
